SCREW CAPPING MACHINE

Abraham Podel, New York, N. Y., assignor to
 Anchor Cap & Closure Corporation, Long
 Island City, N. Y., a corporation of New York

Application March 5, 1932, Serial No. 596,967

18 Claims. (Cl. 226—88)

The present invention relates to sealing machines, and more particularly to a machine adapted to apply screw caps upon containers.

Many difficulties have been encountered in sealing screw caps upon containers. If the caps are applied by hand, it is not feasible to tighten them sufficiently to provide a secure seal, and, on the other hand, if mechanical devices are utilized, the caps are frequently forced too tightly upon the container and cannot be readily removed. In addition, glass containers vary from a true standard in size so that the threads or the cap engaging means do not permit the cap to be rotated thereon with uniformity. In some instances, a relatively shorter turn will properly seal the cap and, upon further rotative effort, the sealing chuck will slip and mar the lacquer of the cap, thus spoiling the attractiveness of the package. Likewise, if mechanical means are utilized and the cap requires a longer turn than the machine is adjusted to provide, the container will not be properly sealed and the contents thereof may spoil. These difficulties are inherent in existing machines and particularly so in devices for applying lug caps upon containers having interrupted threads thereon. Caps of this type usually require only a relatively short turn to seal the cap on the container.

The present invention aims to provide an inexpensive sealing machine adapted to overcome the above difficulties, whereby a satisfactory seal is provided in every instance. The sealing machine of the present invention is adapted to screw caps upon a container or to tighten caps, placed loosely upon the container by hand, to provide a secure seal. This is accomplished by utilizing a cap engaging head and operating means adapted to rotate the caps a definite or predetermined amount, depending upon the relative fit between the glass finish and the cap. In this manner, the caps are tightened uniformly to effect a satisfactory seal in every instance, without marring or deforming the cap.

An object of the present invention is to provide a simple, inexpensive machine for applying screw caps upon containers.

Another object of the invention is to provide a machine adapted to tighten caps upon containers which have been loosely applied thereto by hand.

Another object of the invention is to provide a sealing machine adapted to form a seal of uniform tightness upon containers, without applying the caps too tightly or marring the lacquer thereof.

Another object of the invention is to provide a machine particularly adapted to tighten caps, having lugs in the skirt thereof, upon containers having interrupted or divided threads.

Another object of the present invention is to provide a screw capping machine having means adapted to cooperate with the sealing devices to hold the containers against rotation while a cap is applied thereto.

A further object of the invention is to provide a sealing machine adapted to be adjusted to accommodate containers of various sizes.

Other and further objects of the invention will be obvious upon an understanding of the illustrative embodiment about to be described, or will be indicated in the appended claims, and various advantages not referred to herein will occur to one skilled in the art, upon employment of the invention in practice.

A preferred embodiment of the invention has been chosen for purposes of illustration and description and will be indicated in the accompanying drawings, forming a part of the specification, wherein

Fig. 1 is a side elevational view illustrating a preferred embodiment of the invention;

Fig. 2 is a fragmentary sectional view of a portion of the machine, illustrating the cap applying means;

Fig. 3 is a fragmentary side elevational view, partly in section, illustrating a cap being sealed upon a container, and a preferred mechanism for holding the container against rotation;

Fig. 4 is a sectional view, taken along the line 4—4 of Fig. 3;

Fig. 5 is a sectional view, taken along the line 5—5 of Fig. 2, illustrating means for adjusting the height of the sealing head;

Fig. 6 is a fragmentary sectional view, illustrating the drive and clutch mechanisms;

Fig. 7 is an end view with parts broken away to illustrate the operation of the clutch;

Fig. 8 is a sectional view, taken along the line 8—8 of Fig. 2, illustrating a preferred mechanism for operating the cap applying devices;

Fig. 9 is a sectional view of a slightly different cap engaging head;

Fig. 10 shows another form of a chuck for engaging the caps;

Fig. 11 shows still another form of a chuck for engaging the caps; and

Fig. 12 is an enlarged fragmentary elevational view, illustrating a preferred form of clutch faces.

Referring again to the drawings, and more

particularly to Fig. 1 thereof, there is shown a suitable base 1, provided with legs 2 adapted to be secured to the floor, or other suitable foundation, by means of bolts 4. At the upper end of the base 1, a table or platform 5 is provided, adapted to support a container 6 and a sealing head 7, together with the operative parts therefor.

An upright column 11, providing a support for the sealing means, is secured to the table 5 (see Figs. 1, 2 and 3), having a horizontal sleeve 12 mounted at the upper end thereof, which is adapted to house a drive shaft 14 adapted to be operated by a suitable drive mechanism and a clutch device, described hereinafter. At a convenient position on the column 11, a bracket 15 is mounted, with a bearing aperture 16 therein adapted to receive and guide a vertically movable sleeve 17 for supporting and operating the sealing devices. The sleeve 17 is adapted to be moved upwardly and downwardly by an eccentric mechanism, preferably comprising a crank member 19 keyed upon the rotatable shaft 14, a link member 20 pivoted at one end to member 19 by a pin 21, and a clamp member 22 pivoted to the other end of the link member 20 by a suitable pin 24.

Preferably, the clamp member 22, illustrated in Figs. 1, 2 and 5, comprises a pair of split collar members 25 and 26, adapted to receive and engage the shaft 17 to facilitate adjusting the height thereof. The member 25 is provided with a threaded aperture 27, adapted to engage one end of a bolt member which is slidably disposed through an aperture 30 provided in the member 26. The bolt member 29 is provided with a suitable handle member 31 so that the bolt may be rotated to tighten the members 25 and 26 about the sleeve 17 to clamp the sleeve in position.

The lower end of the sleeve 17 is provided with a pair of slots or cam grooves 32 and 34, adapted to receive a pair of rollers 35 and 36, respectively, mounted upon a suitable member 37 adapted to support the sealing mechanism. The member 37 is inserted into the lower end of the sleeve 17 and is adapted to slide upwardly and downwardly therein, whereby the cam grooves 32 and 34 are effective to guide the rollers 35 and 36 and rotate the member 37. If desired, the upper portion of the member 37 may be provided with an aperture or cup portion 39, adapted to retain oil or grease, and with a pair of distributing grooves 40 leading therefrom to the side portions of the sleeve, whereby the contacting surfaces of sleeves 17 and 37 may be kept lubricated.

The lower end of the member 37 is adapted to be threaded into engagement with a bushing 41, formed integral with a suitable downwardly facing clutch disc 42, having a central aperture 43 for receiving a rod 44 adapted to support the sealing head 7. The rod 44 is slidably suspended within the aperture 43 and the member 37 by means of nuts 45, which rest upon the upper end of the bushing 41 to limit the downward movement of the rod. A corresponding upwardly facing clutch member 47 is threaded upon the rod 44, at 46, and is adapted to engage the clutch face 42 upon relative upward movement of the rod 44. The clutch faces 42 and 47 are, preferably, provided with ratchet teeth 49 (see Fig. 12) adapted to engage upon clockwise rotation and disengage upon counter-clockwise rotation.

The sealing head illustrated in the embodiment, shown in Figs. 1, 2 and 3, preferably com-

prises a substantially cone-shaped disc 50, secured to the lower end 48 of the rod 44, and having a friction surface 51 at the side portions thereof. A cup-shaped member 52 is telescoped about the disc 50 and is slidably mounted with respect to the rod 44. The cup-shaped member 52 is provided with a corresponding friction surface 53, adapted to engage the friction surface 51 to rotate the cup-shaped member whereby the members 50 and 52 form a friction clutch. The member 52 is preferably provided with a flange 54 for securing a suitable cap engaging chuck 55 thereto. The cap engaging chuck 55 may comprise an annular member having an internal inclined zone 56, for engaging the knurled portion 15 of the cap 9, as shown in Fig. 3.

In order to hold the members 50 and 52 in frictional engagement, so that the chuck 55 is rotated with the sleeve 37, when the clutch faces 42 and 47 are effective, a spring member 57 is mounted about the rod 44 so that its lower end abuts against the top portion of member 52 through the intermedium of a washer 59, to hold member 52 downwardly in frictional contact with member 50. The spring 57 is compressed at the upper end thereof by a member 60, threaded upon the rod 44 below the clutch member 47. By moving the member 60 upwardly or downwardly, the spring 57 may be adjusted to regulate the amount of frictional contact between members 50 and 52. It will be understood that the spring 57 may be compressed any desired amount to increase the effectiveness of the friction members 50 and 52.

In some instances, it may be desirable to prevent relative rotation between the friction members 50 and 52. This may be accomplished by increasing the compression on the members 51 and 52 by means of the spring 57. A better way is to utilize a sealing head, such as shown in Fig. 9, 40 wherein a chuck supporting member 58 is connected directly to the rod 44, without the friction discs. The remaining parts of the sealing head may be the same as described above with respect to Fig. 3.

The construction shown in Fig. 9 is particularly applicable where it is desired to turn the cap through a definite predetermined angle in the application thereof. Certain containers for lug screw caps have flat or horizontal thread portions to prevent accidental loosening of the caps. With these containers, the caps should be turned a definite angle so that the lugs will rest on these horizontal portions. There is sufficient flexibility in such caps to permit the same amount of rotation in each instance.

When the sleeve 17 is moved downwardly by the drive mechanism, the chuck 55 engages the cap 9 and moves the rod 44 upwardly with respect to sleeve 37 to make the clutch members 42 and 47 effective. Upon further downward movement of the sleeve 17, the cam grooves 32 and 34 act upon the cam rollers 35 and 36 to rotate the sleeve 37, whereby the clutch members 42 and 47, and the chuck 55, are rotated to apply the cap 50 upon the container. When the downward pressure of the chuck 55 upon the cap becomes excessive, as the cap is screwed home, the friction member 50 is moved relatively downwardly and out of contact with the member 52, whereby the corresponding friction surfaces 51 and 53 disengage. When the sleeve 17 is raised upwardly, the weight of the sealing head causes the rod 44 to move relatively downwardly in the sleeve 37, whereby the teeth of the clutch members 42 and 75

47 disengage, and the sealing head cannot be rotated in a counter-clockwise direction to unscrew the cap.

If desired, markings 48 (Fig. 3) may be provided on the sleeve 37, adapted to indicate the angle which the chuck 55 has been rotated. These markings register with the lower end of the sleeve 17, so that they are readily readable by the operator of the machine during the sealing operations. These markings are also helpful for determining the angle the cap has been rotated upon the container, so that the spring 51 may be adjusted to provide the proper frictional contact between members 50 and 52.

15 Since it is desirable to center the containers properly, with respect to the sealing head, a plurality of concentric, annular grooves 61 are provided on the platform 5, which serve as a guide for the operator placing the containers thereon. 20 In addition, as shown more particularly in Figs. 3 and 4, the present invention provides automatic means for clamping the containers to prevent rotation thereof during the application of closure caps thereto. These means preferably comprise 25 a substantially Y-shaped member 62, suitably attached to the table 5 by means of a bolt 64 extending through a slot 65, provided in member 62, adapted to facilitate adjustment thereof for different sizes of containers. A corresponding 30 Y-shaped member 66 is slidably mounted upon the table by a rod 69, which is adapted to reciprocate within a bearing 70 provided in column 11. The members 62 and 66 are preferably provided with suitable gripping cushions 67, composed of 35 rubber, felt or similar material, which are adapted to hold the containers without danger of breakage.

Referring more particularly to Figs. 2, 3 and 8, there is shown a mechanism adapted to operate 40 the clamping member 66 with the cap applying means. A cam 71 is mounted upon the drive shaft 14, which operates the sealing mechanism for operating the container clamping mechanism in timed relation to the sealing mechanism. The 45 cam member 71 is provided with a cam surface 72 which engages cam rollers 77 for reciprocating a slide member 74, having a slot 75 therein adapted to receive a guide roller 76 on the shaft 14.

The reciprocating movement of the slideable 50 member may be transmitted to the clamping member 66 by any suitable connecting devices. For example, a bushing 80 may be provided at the lower end of member 74, so that the upper end of a vertical rod 81 may be secured therein. The 55 lower end of the rod 81 is slidably mounted in a suitable bearing portion 83, provided in a sleeve member 84, which may be slidably disposed within a bearing aperture 85 in the supporting bracket 15. A roller 86 is mounted adjacent to the member 84 to facilitate upward and downward movement of the sleeve 84. In order that the rod 81 and the sleeve 84 operate in a steady manner, without sudden jerks, a suitable spring 87 is coiled about the rod 81, which is tensioned by means of 60 a flange 82 at the upper end of the rod, and a suitable extension provided within the sleeve 84, adapted to engage and provide a seat for the lower end of the spring. The sliding movement of the rod is limited within the bearing portion 83 of 65 the sleeve by a groove 78, provided in the rod 81, which defines upper and lower abutting portions adapted to engage a suitable key member 89 secured to member 84. In this manner, when the rod 81 is moved downwardly, the spring 87 is compressed until it offers sufficient resistance to im-

part downward movement to the sleeve 84 and, likewise, upon upward movement of the rod 81, the tension of the spring is gradually relieved until the lower end of the grooved portion 78 engages the key member 89 to raise the sleeve upwardly. These members effect a resilient connection which prevents excessive or sudden forces from being exerted upon the clamp member 66.

The vertical movement of these connecting devices is transformed into horizontal movement by 10 providing a connecting link 90 at the lower end of the sleeve 84, which is, in turn, connected to a bell crank 91 mounted at 92 upon the supporting column 11. To operatively connect the bell crank to the clamp member, a suitable slideable 15 member 94 is linked to the bell crank by means of a pin 96 extending through an aperture 95 in the member 94. The slideable member 94 is provided with a bearing portion 97, adapted to receive the rod 69 of the clamp member 66, which 20 may be secured thereto in any suitable manner. Preferably, as illustrated herein, a bolt member 99 is threaded transversely into the member 94 and is adapted to engage spaced indentations 100, provided in the rod portion 69. The bolt member 99 is adapted to be unscrewed, whereby the 25 position of the container gripping clamp 66 may be adjusted so that the bolt engages any of the notches 100 along the rod 69, depending upon the desired position of the clamp 66. In order that 30 the rod 69 does not slide freely in the aperture 97 when the bolt 99 is unscrewed, a pin 101 is oppositely disposed with respect to the bolt and adapted to engage corresponding notches 100, provided on the other side of the rod 69. The pin 101 is 35 held resiliently against the rod 69 by a spring member 102 abutting against a flange 104 on the pin, and a holding member 105 secured to the member 94. In this manner, the rod 69 may readily slide within the bearing 97 to adjust the 40 position of the clamp 66 by withdrawing the pin 101, and is temporarily held against movement when the pin is effective.

Fig. 10 illustrates a slightly different type of chuck, which comprises a member 106 connected 45 to the lower end of the rod 44 and having a disc 107, of composition rubber or the like, secured thereto by means of bolts 108. Other material, such as felt, may also be utilized, depending upon the desired friction between the cap and chuck. 50 The lower surface of the disc is adapted to frictionally engage the top portion of the cap, and, upon rotation of the sealing head, the cap is screwed upon the container. To facilitate a better grip between the disc and the cap, the lower surface of the disc may be grooved or cross-hatched, as indicated at 109. The advantage of this type of chuck is that it is adapted to apply caps varying in size, without any adjustment.

In Fig. 11, there is shown another form of chuck 60 adapted to engage the top of dome-shaped caps. To accomplish this, the lower surface of the chuck is concave, so that it registers with the convex portion of the cap. This type of chuck operates in the same manner as the chuck shown in Fig. 10 65 and eliminates the necessity of a frictional clutch, or other complicated devices, to facilitate proper application of the cap upon the container.

A preferred drive mechanism is illustrated more particularly in Figs. 1, 6 and 7, comprising a 70 motor 110 secured to the platform 5, and a clutch mechanism 112, supported by a column 113 and operatively connected to the motor by means of a belt 114 encased within a suitable guard 115. The belt 114 is mounted upon a pulley 116, secured 75

to a shaft 117 having a worm gear 119 thereon, adapted to mesh with and rotate a corresponding gear 120 rotatably mounted upon a bearing 121 on shaft 14. The gear 120 has an attached plate member 122, with an aperture 124 therein adapted to engage suitable means for operatively connecting the shaft 14 with the gear 120. A hand wheel 118 is attached to the end of the shaft 117, for manually operating the machine to make 10 adjustments and the like.

As shown in Figs. 6 and 7, the shaft 14 extends through the bearing 121, and the protruding end thereof is provided with a member 125 adapted to support means for periodically engaging the 15 aperture 124 in the plate 122. These means preferably comprise a suitable plunger 126, slidably disposed in a slot 127 in member 125, which is normally held in engagement with the plate member 122 by means of a spring member 129. 20 A suitable roller 130 is mounted, at 131, upon the plunger 126, to be engaged by a cam member 132 mounted adjacent to member 125. The cam member 132 is provided with an inclined portion 134 adapted to engage the roller 130 and with 25 draw the plunger 126 from the aperture 124.

The cam member 132 is secured to an arm 136, pivoted at 137, which is held in position by a spring member 139. The arm 136 is adapted to be oscillated by means of levers 138 and 140, operatively connected to a treadle 141 mounted on the legs 2 of the supporting standard 1. By pushing the treadle 141 downwardly, the lever 138 oscillates the lever 140 to operate the arm 136, which is then effective to move the cam away 35 from the roller, whereby the roller is released and the spring 129 slides the plunger 126 into the aperture 124 of the clutch plate 122. In this manner, the member 125 is adapted to rotate the shaft 14 for driving the machine. When pressure on the treadle is released, the spring 139 returns the arm 136 and the cam 132 to its normal position, whereby the roller 130 is engaged by the cam to move the plunger 126 out of engagement within the plate to stop the rotation of the 40 drive shaft 114. It will be understood that other drive mechanisms and clutch devices may be advantageously utilized, but the above construction is desirable because it automatically permits the sealing devices to be operated for one complete sealing cycle, thus eliminating excessive wear of the machine and preventing accidents likely to be caused by continuously moving sealing means.

In adjusting the machine for operation, a container is centered with respect to the sealing head 7, by means of the circular grooves 61 on the platform 5, and the stationary gripping member 62 is adjusted by means of bolt 64 to position the container properly. The movable gripping member 66 is then moved towards the container by turning over the machine by means of the hand wheel 118, so that the container is engaged by the Y-shaped portion of the member 66. The rod 69 may then be slidably adjusted with respect 55 to member 94 by securing the bolt 99 in the proper notch so that the movable clamping member 66 firmly engages the container to hold it against the stationary clamping member 62. When these adjustments have been made, a closure cap 9 is loosely applied upon the container, and a cap engaging chuck 55, of proper size, is connected to the sealing head. The hand wheel 70 118 is again turned over so that the sealing head is in its lower position and the chuck engages the 75 closure cap. The height of the sealing head is

then adjusted by means of the clamping member 22, by sliding the sleeve 17 into its proper elevation and clamping it in position by the handle 31.

When the sleeve 17 is in its lower operating position, the chuck should rest upon the cap, the 5 degree lines 58 on the sleeve 37 then indicate the desired angle of turn of the chuck. To control the desired angle of turn, which, for example, may be 90°, the height of the sleeve is adjusted 10 so that the cam grooves are effective to rotate the chuck until the lower end of the sleeve 17 registers with the 90° mark. Generally, the angle of turn required to apply the cap upon the container 15 to provide a secure seal, depends upon the number of lugs in the cap or the pitch of the threads. Preferably, the exact angle of rotation is first determined by applying caps upon the containers by hand, to provide the desired seal. After these 20 adjustments have been made, the machine is operated by turning the hand wheel and, if all parts move freely and a satisfactory seal is effected, the power drive may be started.

Preferably, containers having caps loosely applied thereto are fed to the machine by an operator who places them against the stationary 25 clamping member 62. However, it will be understood that automatic conveying devices may be utilized to present the containers to the sealing machine. After a container has been positioned, the treadle 141 is pushed downwardly, whereby 30 the levers 138 and 140 operate the arm 136 to move the cam 132 away from the roller 130, and the spring 129 is effective to slide the plunger 126 against the clutch plate 122. As the drive gears 119 and 120 are rotated, the plate 122 is 35 moved in position so that the plunger 126 registers with the aperture 124, to connect the shaft 14 to the drive means. Upon rotation of shaft 14, the cam 71 slides the member 74 and the rod 81 downwardly to operate the bell crank which 40 slides the movable clamping member 66 into engagement with the container to hold it against rotation. At the same time, the eccentric members 19 and 20 move the supporting clamp 22 and the sleeve 17 downwardly, whereby the chuck 45 55 55 engages the cap. Upon further downward movement, the clutch faces 42 and 47 engage each other, and the sleeve 37 slides upwardly into the sleeve 17. The cam rollers 35 and 36 ride within the grooves of the sleeve 17 to rotate the 50 chuck to apply the cap upon the container. During the sealing of the cap, the markings 58 indicate the angle which the cap has been rotated. If the resistance to downward movement of the chuck 55 becomes excessive, the member 50 continues to move relatively downwardly against the 60 resistance of spring 57, whereby the friction members 50 and 52 disengage to prevent further rotation of the sealing means. If resistance to rotation of the cap becomes excessive, the friction surfaces 51 and 53 will slip to prevent further 65 rotation of the chuck. The allowable sealing effort may be predetermined by adjusting the tension of the spring by raising or lowering the member 60 on the supporting rod 44. In many 70 instances, it may be desirable to utilize the sealing heads illustrated in Figs. 9 and 10. The operation thereof is similar to the preferred embodiment, except that the angle of rotation of the chuck is always the same and is not dependent upon the relative fit between the cap and container.

Reverse rotation of the chuck, which would unscrew the cap, is prevented, since the ratchet teeth 49 of the clutch members 42 and 47 repel 75

these members on backward rotation to make the clutch ineffective.

As the shaft 14 and the member 125 complete one revolution, the roller 130 engages the inclined surface 134 of the cam 132, and moves the plunger 126 away from the clutch face 122, whereby further rotation of the shaft 14 ceases.

While the preferred embodiment has been described as being particularly adapted for sealing or tightening lug type caps upon containers, it will be understood that the present invention contemplates that the machine may be utilized for applying caps having continuous threads. To accomplish this, a suitable sleeve having cam 15 grooves therein adapted to rotate the sealing chuck a desired angle, for example 180° or more, is substituted for the sleeve 17. The other parts of the machine operate in the same manner as described heretofore and facilitate the sealing of 20 screw caps having continuous threads, without sacrificing any of the advantages of the present invention.

It will be seen that the present invention provides a machine adapted to tighten or seal screw caps upon containers to effect a secure and uniform seal in every instance, thereby overcoming the disadvantages of existing machines. The present machine can accommodate containers varying in size and may be readily adjusted to 30 provide the proper rotative effort required to seal the cap effectively upon a container, without marring the lacquer of the cap or sealing the cap too tightly. The present invention further provides container gripping means which are likewise adjustable for different sizes of containers and are operative in timed relation with the sealing means to hold the containers in position against rotation, without danger of being broken. The machine is simple and inexpensive in construction and is designed to prevent injury to the person operating it. The present machine is rugged in construction and can readily withstand the rough usage to which it may be subjected.

As various changes may be made in the form, construction and arrangement of parts without departing from the spirit and scope of the invention and without sacrificing its advantages, it is to be understood that all matter herein is to be interpreted as illustrative and not in a limiting sense.

Having thus described my invention, I claim:

1. In a screw capping machine, the combination of a chuck for frictionally engaging a closure cap, reciprocating means for raising and lowering said chuck into and out of engagement with a cap mounted on a container, means for operatively connecting said chuck to said raising and lowering means to slidably suspend said chuck from said raising and lowering means, 55 means associated with said connecting means for rotating said chuck to apply a cap when downward movement thereof is stopped by a cap on a container, said rotating means being effective to rotate said chuck connecting means in 60 the opposite direction when said reciprocating means move upwardly, and a clutch for preventing rotation of said chuck in said opposite direction.

2. In a sealing machine, the combination of a 70 cap engaging member, a cup-shaped member connected to said cap engaging member having a cone-shaped friction surface, on the inner portions thereof, supporting means within said cup-shaped member having a corresponding friction 75 surface adapted to engage said first surface, a

spring member adapted to maintain the effective frictional contact between said surfaces until downward pressure of the cap engaging member on a cap becomes excessive, and means for rotating said supporting means, whereby said cap engaging means is rotated to screw a cap upon a container.

3. In a sealing machine for applying screw caps upon containers, the combination of a column, having a cam slot therein reciprocating 10 means for moving said column upwardly and downwardly, a rotatable cap engaging chuck adapted to move downwardly with said column, and means slidable within the cam slot of said column for operatively connecting said chuck to 15 said column said cam slot having a curved contour at its lower end adapted to rotate said slideable means, and chuck a predetermined amount to screw a cap upon a container immediately when the chuck engages the cap and further 20 downward movement of the chuck is prevented, said means slideable in said slot being effective to position said chuck for a succeeding rotating operation upon upward movement of said reciprocating means.

4. In a device for screwing caps upon a container, the combination of a sleeve having a cam slot, means for reciprocating said sleeve, a rotatable cap engaging member, means associated with said sleeve for operatively connecting said 30 cap engaging member to said sleeve, said means having projections confined in said cam slot for rotating said cap engaging member through a predetermined angle upon the commencement of lineal movement of said sleeve with respect 35 to the cap engaging member, whereby said cap engaging member is adapted to screw a cap upon a container said cam slot having a curved contour at its lower end whereby said rotating means are effective immediately when downward movement of the chuck is stopped by the cap on the container.

5. In a sealing machine, the combination of a sleeve having a pair of cam grooves therein, a member slidably mounted in said sleeve, a pair 45 of rollers attached to said member disposed in said cam grooves adapted to effect relative rotation between said sleeve and member, clutch members connected to said slideable member, a chuck operatively connected to said clutch members 50 adapted to engage a closure cap on a container, and means for moving said sleeve downwardly to place said chuck on the closure cap and make said clutch effective, whereby the rollers ride in said cam grooves to rotate the slideable 55 member and chuck to screw the cap upon the container.

6. In a sealing machine, the combination of a sleeve having cam grooves therein, a member disposed in said sleeve having rollers thereon 60 adapted to ride in said grooves to effect relative rotation of said sleeve and member, a clutch mechanism operatively connected to said member, cap gripping means friction means for connecting said cap gripping means to said clutch 65 mechanism, and means for lowering said sleeve to move said cap gripping means into engagement with a cap on a container to make said clutch effective whereby further downward movement of the sleeve effects rotation of said 70 member, clutch mechanism and cap gripping means to screw the cap on the container, said friction means being effective to stop rotation of said cap gripping means when the cap is screwed home on the container.

7. In a screw capping machine, the combination of a rotatable cap engaging member, reciprocating means for supporting and moving said member downwardly into engagement with a closure cap on a container, means for rotating said member immediately when moved into engagement with the closure cap, a ratchet clutch associated with said moving and rotating means for rendering said rotating means effective when said member engages a cap, and means associated with said cap engaging member for rendering said rotating means ineffective when said member has turned the cap through a predetermined angle, said clutch being rendered ineffective when said moving means raise said member upwardly and out of engagement with the closure cap.
8. In a sealing machine, the combination of means for screwing a cap upon a container, a member adapted to center the container with respect to said means, a movable member adapted to engage the container and clamp it against said first member to hold the container against rotation, said movable member having an extension provided with spaced notches, a slideable member having means secured therein for engaging one of the notches on said extension to adjust the position of said movable member with respect to said first member, and means for operating said slideable member and said movable member, said last means being effective in timed relation with said cap applying means.
9. In a sealing machine, the combination of a platform adapted to support a container to be sealed, means for screwing a cap upon the container, a member bolted to said platform adapted to engage and center the container with respect to said capping means, a movable member adapted to clamp the container against said first member, means associated with said movable member for adjusting the position thereof with respect to said first member, and means for operating said clamping member in timed relation with said capping means.
10. In a sealing machine, the combination of a sleeve having cam slots therein, devices for reciprocating said sleeve, a cap engaging chuck, means for operatively connecting said chuck to said sleeve, said means having rollers associated therewith confined in said cam slots adapted to ride in said cam slots, said means and sleeve being relatively slideable whereby downward movement of said sleeve with respect to said means will cause said rollers to ride upwardly in said cam slots and rotate said means and said cap engaging chuck, said slots having portions adapted to rotate said means when said chuck engages the cap and portions above said first portions adapted to permit said rollers to move upwardly without rotation of said means, and means associated with said reciprocating means for adjusting the position of said sleeve to control the effective angle of rotation of said chuck connecting means.
11. In a sealing machine, the combination of a sealing head adapted to rest by gravity on a cap on a container to frictionally engage the closure cap, and a sleeve relatively slideable with said head adapted to support said head, a ratchet clutch associated with said head, reciprocating means for moving said sleeve upwardly and downwardly, and means associated with said head and sleeve for effecting relative rotation between said sleeve and head when said reciprocating means are effective, said ratchet clutch rendering said rotating means ineffective during upward movement

- of said sleeve while said head is engaging the cap.
12. In a screw capping machine, the combination of a sleeve having cam slots therein, means for reciprocating said sleeve, a chuck holder connected to said sleeve having rollers thereon for riding in said cam slots, a ratchet member secured to said chuck holder, a second ratchet member slidably connected to said chuck holder adapted to engage said first ratchet member when said first ratchet member is rotated in a 10 clockwise direction, a friction disc connected to and rotatable with said second ratchet member, a cap engaging chuck having a friction surface abutting against said friction disc, said chuck being mounted upon said friction disc, and 15 silent means between said chuck and second ratchet member for holding the friction surface of said chuck against said friction disc.
13. In a screw capping machine, the combination of a column, a rotatable cap engaging 20 chuck for screwing a cap on a container, said chuck having a friction clutch therein, means operatively connected to said chuck and said column for rotating said chuck through a predetermined angle upon downward movement of 25 said column, and means for moving said column downwardly whereby said cap engaging chuck is adapted to be moved into engagement with a closure cap and is rotated to screw the cap upon a container, said friction clutch being adapted to 30 stop the movement of said chuck when resistance of the cap to downward movement or rotation becomes excessive.
14. In a sealing machine, the combination of a sleeve, a rotatable cap engaging chuck operatively connected to said sleeve, a clutch mechanism associated with said chuck, means for moving said sleeve to move said chuck into engagement with a cap on a container, and cam means in said sleeve for rotating said clutch and 35 chuck, said cam means and clutch being effective in response to said chuck engaging a cap.
15. In a screw capping machine the combination of a vertically reciprocating sleeve, a ratchet clutch rotating means operatively connecting 45 said clutch to said sleeve, and a cap engaging chuck connected to said clutch adapted to be rotated in one direction to screw a cap on a container, said clutch comprising a pair of members having ratchet teeth thereon adapted to engage 50 when the sleeve is moved downwardly and said chuck engages a cap on a container to rotate the chuck, said ratchet teeth disengaging when the sleeve is moved upwardly whereby rotation of the chuck in the other direction is prevented. 55
16. In a screw capping machine, a column having cam slots therein for rotating a cap engaging means less than 200°, a cap engaging chuck, means operatively connected to said chuck and slidably associated with the slots in said column, 60 an adjustable clutch associated with said chuck and connecting means adapted to stop rotation of said chuck when the cap is screwed on the container, means for moving said column downwardly to cause said slots to rotate a predetermined angle, and markings on said last means adapted to indicate the angle said chuck has been rotated so that the clutch may be adjusted to stop rotation of the chuck after the chuck has been rotated a predetermined angle. 65
17. In a screw capping machine, the combination of an annular member for engaging a closure cap, a substantially cup-shaped member having said annular member connected thereto, said cup-shaped member having a down- 70

wardly facing friction surface, a disc member mounted within said cup-shaped member having an upwardly facing friction surface for engaging said friction surface of said cup-shaped member, a spring for normally holding said friction surfaces in engagement, said disc and cup-shaped member being adapted to be moved apart in resistance to said spring, and means for moving said disc downwardly and rotating said disc to 5
10 rotate said cup-shaped member and annular member to apply a cap on a container, said spring being adjustable to render engagement between said friction surfaces ineffective when rotative forces between said friction surfaces become excessive or when downward forces exerted by 15 said annular member on the cap become excessive.

18. In a screw capping machine for rotating screw caps a predetermined angle, the combination of a movable sleeve having cam slots therein, a cap engaging means for rotating screw caps upon containers, a member slidable within said sleeve and operatively connecting said cap engaging means to said sleeve, rollers on said member confined in said cam slots, said cam slots being adapted to rotate said member and cap engaging means a predetermined angle upon movement of said sleeve, said member having markings thereon adapted to register with the lower end of said sleeve to indicate the angle of rotation of said member and cap engaging means, and means for adjusting said movable sleeve to determine the angle of rotation. 10 15
